UNITED STATES PATENT OFFICE.

RALPH E. WILSON, OF DALLAS, TEXAS.

COTTON-SEPARATING MACHINE.

Application filed November 22, 1926. Serial No. 148,940.

This invention relates to a machine designed primarily for separating cotton from the dried hulls. A large percentage of the cotton grown in the United States is produced where frost and cold weather kill the cotton plants before the bolls have opened naturally to the point where the cotton can be picked out of the bolls in the field by hand. In order that the cotton thus affected 10 may be marketed it is necessary that some means be provided for opening and tearing apart the bolls and removing the cotton from the hulls before ginning.

It is an object of the present invention to 15 provide efficient means whereby the cotton, in the condition described, can be quickly and thoroughly torn apart and practically all of the cotton fibers removed from the hulls.

20 A further object is to effect the separation by means of intermittent application of the treated material to the separating teeth, the hulls and other trash separated from the fibers being delivered by gravity from the machine.

25 It is the practice frequently to utilize, in connection with cotton gins, a boll breaker for separating the hulls from the cotton or what is known as "belley" cotton. The present invention is not designed for use as a boll breaker but, on the contrary, is to be employed for treating the cotton while passing from the boll breaker to the gin.

With the foregoing and other objects in 30 view which will appear as the description proceeds, the invention resides in the combination and arrangement of parts and in the details of construction hereinafter described and claimed, it being understood that changes in the precise embodiment of the invention herein disclosed may be made 35 within the scope of what is claimed, without departing from the spirit of the invention.

In the accompanying drawings the preferred form of the invention has been 40 shown.

In said drawings,

45 Figure 1 is a central vertical section through the cotton separator.

Figure 2 is a vertical transverse section therethrough on the line 2-2, Figure 1.

50 Figure 3 is a view partly in section and partly in elevation of the racks and operating means in one position.

Figure 4 is a similar view showing another 55 set of racks and their operating means in one position.

Figure 5 is a view partly in side elevation and partly in section of a portion of a cotton separator showing a modified means for 60 operating the racks.

Figure 6 is a side elevation of the operating means shown in Figure 5, a portion of the separator being shown in section.

Figure 7 is a section through a modified 65 form of separator designed for use upon a gin.

Figure 8 is an elevation of the machine shown in Figure 7 and showing that side 70 thereof containing the rack operating mechanism.

Figure 9 is a plan view of the rack operating mechanism shown in Figure 8, a portion of the separator being shown in section.

Figure 10 is an elevation of one of the 75 racks and its operating means, one position being indicated by full lines and another position by broken lines.

Figure 11 is a section through another 80 form of separator.

Referring to the figures by characters of reference 1 designates a closed housing having an inlet or feed hopper 2 at its upper end and an outlet hopper 3 formed by the converging walls of the bottom portion of the housing, this outlet hopper opening into the casing 4 of a vacuum feeding wheel 5 mounted for rotation in the casing 4 and adapted to discharge into a blow pipe or flue 6. A suction pipe 7 communicates with the cotton outlet 8 of the housing, there being guard plates or shields 9 extending inwardly from the upper and lower walls of the outlet 8 and close to the periphery of a 90 rotatable dosing brush 10 journaled within the housing.

95 Superposed shafts 11 and 12 are journaled in the housing and mounted on and rotatable with the upper shaft 11 is a toothed cylinder 13 while another similar toothed cylinder 14 is secured to and rotates with the shaft 12. A stripper roller 15 is journaled in the housing and is supported close to the upper portion of the periphery of cylinder 100 13 and adjacent one side of the hopper 2. Another stripper roller 16 is arranged close to the uppermost portion of the lower cylinder.

der 14 and back of a shield plate 17 extending downwardly close to and beneath the cylinder 13.

The brush 10, the cylinders and the stripper rollers and other rotating parts can be operated by any suitable mechanism provided for that purpose. For example, a pulley 18 can be secured to the shaft 11 and another pulley 19 can be secured to the shaft 12. An idler pulley 20 can be journaled on one side of the housing, this pulley being engaged by an endless belt 21 which extends downwardly into engagement with a pulley 22 carried by the shaft 23 of the vacuum feeder 5. From this pulley 22 the belt can be extended over an idler 24 and thence under and into engagement with the pulley 19, over a pulley 25 secured to the shaft 26 of the stripper roller 16, partly around a pulley 27 carried by the shaft 28 of brush 10, and thence under and into engagement with pulley 18 and back to the pulley 20. A pulley 29 carried by the shaft 26 can receive motion from a belt 30 driven by any suitable means.

Mounted on the pulley 19 is a short endless belt 31 used to drive the stripper roller 16 and another short endless belt 32 is mounted on the pulley 18 and utilized for driving the stripper roller 15.

Extending transversely within the housing 1 are superposed rock shafts 33, 34, 35 and 36. Fixedly connected to and extending radially from each of these shafts is a rack, said racks being indicated at 37, 38, 39 and 40 respectively. The racks illustrated are formed of spaced fingers but it is to be understood that they can be made of solid boards or any other materials desired.

The shafts are arranged in groups, the shafts 33 and 35 being coupled together for simultaneous operation while the shafts 34 and 36 are also coupled together. This will be seen by referring particularly to Figures 3 and 4. Shafts 33 and 35 are provided at one end with crank arms 41 connected by a bar 42 to which they are pivotally connected. The lower end of this bar rests upon and is adapted to be actuated by a rotatable cam 43 secured to a shaft 44 which can receive motion through a pulley 45 and a belt 46 from a pulley 47 secured to the shaft 12.

The shafts 34 and 36 are provided at one end with crank arms 48 pivotally connected to a bar 49 which rests upon and is adapted to be actuated by a rotatable cam 50 secured to the shaft 44. The two cams are so arranged on shaft 44 as to actuate the bars 42 and 49 alternately. In other words while the bar 49 is in its lowermost position the bar 42 can be moving upwardly under the action of its cam 43, and vice versa.

The racks 37 and 38 are adapted to extend close to and cooperate with the upper toothed cylinder 13 which the racks 39 and 40 extend close to and are adapted to co-

operate with the lower toothed cylinder 14. The operation of the structure is as follows: Assuming that the cylinders 13 and 14 are rotating at a high speed in the direction indicated by the arrows in Figure 1, the stripper roller would also be rotating in the direction indicated by the arrows while the doffing brush will act to strip cotton fibers from the teeth of the cylinders and direct the cotton into the suction pipe 7 by way of the outlet 8. The periphery of the brush travels at a higher speed than the peripheries of the cylinders to permit this action.

The cotton to be treated is directed through the outlet 2 and will come upon and be supported by the upper rack 37 so that the material will thus be caused to gravitate against the teeth of the upper cylinder 13 which will grip portions of the cotton and tear the same from the hulls, this action being facilitated by the stripper roller 15. After a predetermined interval the cam 43 thrusts upwardly against the bar 42 so as to cause the racks 37 and 39 to swing downwardly from the positions shown in Figure 1 and in full lines in Figure 3 to the position shown by broken lines in Figure 3. Just prior to this movement, however, the cam 50 thrusts upwardly against the bar 49 so that the racks 38 and 40 are swung from the full line positions shown in Figure 4 to the dotted line position shown in said figure. Thus as the rack 37 swings downwardly the material supported thereby will gravitate onto the previously raised rack 38 along which the material will gravitate so as to again come against the toothed surface of the cylinder 13 where a further separation is effected. After a predetermined time interval the rack 38 swings downwardly but immediately prior thereto the rack 39 has been raised by the cam 43 acting on the bar 42. Thus the material gravitates off of the rack 38 onto the rack 39 along which it will slide against the surface of the toothed cylinder 14. This will result in a further separation of the cotton from the hulls. Thereafter rack 39 will swing downwardly and deposit the material on the rack 40 which has moved upwardly. Here a final separation of the cotton from the hulls will take place, after which rack 40 will swing downwardly and the hulls and other trash remaining will gravitate to the vacuum feeder and be delivered into the flue or flow pipe 6. As the cotton is separated away and carried past the stripper roller, it will be doffed from the toothed cylinders by the brush 10 as before explained and directed into the suction pipe 7.

Importance is attached to the use of the superposed alternately operating means for retarding the mass of cotton while permitting it to gravitate against the toothed cylinders, thereafter releasing said mass so that

it can rotate as it falls onto the next rack along which it gravitates for re-engagement with the toothed cylinder. By using an intermittent retarding means of this kind particularly in connection with superposed separating units such as illustrated in Figure 1 wherein cylinder 13 constitutes a part of one unit and cylinder 14 constitutes a part of the other unit, a very rapid and thorough separation is insured.

It will be obvious that various changes may be made in the construction of a machine designed to carry out this operation. For example, instead of utilizing cams and connecting bars as shown in Figures 1, 3 and 4, the racks with their crank arms, indicated at 51 in Figure 5 can be connected to bars 52 and 53, one of these bars being provided for each pair of racks. To each bar a pitman 54 can be connected, this pitman receiving motion from an eccentric 55 carried by a shaft 56. With an operating mechanism of this type the up and down movement of each rack is more gradual than where a cam such as shown in Figures 3 and 4 is utilized. The cam allows the rack to swing downwardly gradually but they will snap quickly to elevated position when relieved from the thrusting action of the cam.

Instead of utilizing a plurality of toothed cylinders with a group of racks associated with each cylinder, a structure such as illustrated in Figure 7 can be employed. This structure, by reason of its compact arrangement, is particularly designed for use on a cotton gin. This structure includes a housing 57 having an inlet opening 58 at the top thereof, an outlet trough 59 in the bottom thereof, and a cotton chute 60 leading from an outlet 61 in the wall of the housing. In this modified form of machine a toothed cylinder 62 is carried by a shaft 63 journaled in the housing. Interposed between this cylinder and the bottom portion of the outlet 61 is a screen 64 above which is located a rotatable doffing brush 65. Feed rollers 66 are arranged within the inlet opening 58 and interposed between one of these feed rollers and the cylinder 62 is a stripper roller 67. A shield 68 extends between the stripper roller 67 and the feed rollers 66 thereabove so as to prevent the hulls and other trash from being carried by the stripper roller toward the doffing brush.

The feed rollers 66 are provided with meshing gears 69 such as commonly employed to cause the rolls to rotate in opposite directions respectively. One of these feed rolls has a ratchet wheel 70 rotatable therewith, there being a lever 71 journaled on the shaft 72 of said roller and carrying a pawl 73 at one end which meshes with the ratchet wheel. Parallel links 74 connect the lever 71 to a link 75 carrying another pawl 76 which engages the ratchet wheel 70, one

of the links 74 being attached to one end of a lever 77 fulcrumed as at 78. The other end of lever 77 is pivotally connected to an arm 79 adjustably attached to a segment 80. This segment is pivotally attached to a pitman 81 driven by a wrist pin 82 carried by a small gear 83. Gear 83 is connected to and rotates with a large gear 84 and this latter gear meshes with and receives motion from a small gear 85 secured to and rotating with the shaft 63 of the toothed cylinder 62. The gear 83 meshes with a last gear 86 journaled on one side of the housing and having a shaft 87 to which are secured separate disks 88, 89 and 90. Disk 88 has a tripping pin 91 extending laterally therefrom and a similar pin 92 is extended laterally from the disk 89. A third pin 93 is extended laterally from the disk 90. This arrangement has been illustrated in Figure 9.

Arranged between one wall of the housing 57 and the toothed cylinder 62 are superposed shafts 94, 95 and 96 each of which has a rack 97, 98 or 99 extending radially therefrom toward the periphery of the cylinder 62. Shaft 94, as shown in Figure 8 has a crank arm 100 pivotally connected by a link 101 to one end of a lever 102 extending into the path of the pin 91. A crank arm 103 is extended radially from the shaft 95 and is connected by a link 104 to one end of a lever 105 projecting into the path of the tripping pin 92. A radial arm 106 is extended from the shaft 96 and is connected by a link 107 to one end of a lever 108 which projects into the path of the tripping pin 93. Weights 109 are attached to the respective shafts 94, 95 and 96 and act to hold the levers 102, 104 and 108 normally lowered at their free ends and with the racks normally elevated.

The worm conveyor 110 can be arranged within the trough 59 for the purpose of removing trash deposited in the trough.

Any desired means can be employed for driving the stripper roller. For example a pulley 111 can be secured to the shaft 112 of said roller and can be driven by a belt 113 driven by a pulley 114 carried by the shaft 63.

In operation the cotton to be treated is directed into the inlet 58 where it is engaged by the rotating feed rollers 66 and forced downwardly. The speed of rotation of these feed rollers depends upon the adjustment of the parts 79 and 80. The rotating gear 83 oscillates the lever 80 through the pitman 81 and the amount of motion transmitted by this oscillating lever of course depends upon the distance between the fulcrum of said lever and the point of connection between the lever and the link 79. As lever 80 oscillates lever 77 will also be oscillated and such oscillation will result in the actuation of the pawls 73 and 72 and the intermittent

rotation of the ratchet wheel 70 and of the two feed rollers. As the feed rollers oscillates motion is transmitted to the disk 88, 89 and 90. The pins on these disks are so located that the levers 102, 105 and 108 will be actuated thereby in properly timed succession. For example as the cotton is directed downwardly onto the toothed cylinder 62 it will be supported by the rack 97 and gravitate therealong against the toothed cylinder so that cotton will be pulled from the hulls and conveyed to the doffing brush. After this operation has continued for a predetermined time the lever 102 is tripped to cause the rack 97 to swing downwardly, thereby discharging the material thereon to the rack 98. The operation is then repeated, a new supply of cotton being delivered to the rack 97 while the cotton previously acted on will be supported by the rack 98 and be held by gravity against the toothed cylinder. Thereafter, after a predetermined interval, the lever 105 will be tripped and the rack 98 swing downwardly. This will cause the cotton to slide off of rack 98 onto rack 99. The cotton previously supported by the rack 97 will be delivered onto the rack 98 by a second tripping of lever 102 while a new supply of cotton will be delivered onto the rack 97 after it has been tripped. Thus cotton will be acted on at three different places on the cylinder, the new supply being engaged by the teeth while being supported on the rack 97, the previously treated supply being engaged by the toothed cylinder while the supply is supported on rack 98, and the lower rack 99 holding against the cylinder the cotton which had previously been supported by the two racks thereabove. Thereafter the cotton on rack 99 will be dumped by the tripping of lever 108 and the trash, including the hulls, supported by this rack will be delivered to the trough 59. Previous thereto, however, practically all of the cotton fiber has been removed from the hulls by the toothed cylinder 62 and conveyed to the doffing brush.

What is claimed is:

1. The combination with a toothed cylinder mounted for rotation and a stripper roller thereabove and adjacent thereto, of means for feeding cotton by gravity to the cylinder, a plurality of movable racks, and means for positively actuating the racks for cooperation with the cylinder to intermittently retard the gravitation of the cotton and presenting it to the cylinder.

2. The combination with a housing having a cotton inlet at its upper and trash receiving means adjacent its lower end, of a toothed cylinder mounted for rotation within the housing between the inlet and the trash receiving means, there being a cotton outlet adjacent the cylinder, means for rotating the cylinder to move its teeth against the cotton

gravitating from the inlet, a plurality of movable racks, means for positively actuating the racks for cooperation with the cylinder to intermittently retard the cotton during its gravitation and present the same to the cylinder, a stripper cooperating with the cylinder, and means interposed between the cylinder and the outlet for doffing cotton from the cylinder and directing it to the outlet.

3. The combination with a housing having a cotton inlet at the top thereof, trash receiving means in communication with the bottom of the housing, and a cotton outlet, of a toothed cylinder mounted for rotation within the housing adjacent the outlet below the inlet, a plurality of movable racks, means for positively actuating the racks for cooperation with the cylinder to intermittently retard gravitation of cotton from the inlet and intermittently present the cotton to the cylinder, means for rotating said cylinder to advance the teeth thereof into the retarded cotton and conveyed toward the outlet, stripping means cooperating with the cylinder, and doffing means adjacent the cylinder and outlet.

4. The combination with a housing having a cotton inlet, trash receiving means at the bottom of the housing, and a cotton outlet, of a toothed cylinder mounted for rotation within the housing, superposed racks movably mounted within the housing and cooperating with the cylinder to retard cotton, means for automatically and positively actuating the racks in properly timed succession to successively stop and release cotton gravitating from the inlet and to present the stopped cotton to the cylinder, means for rotating the cylinder to advance its teeth into the stopped cotton, a stripper cooperating with the cylinder, and means for doffing cotton from the cylinder and directing it to the outlet.

5. The combination with a housing having an inlet in the top thereof, trash receiving means communicating with the bottom thereof, and a cotton outlet, of a toothed cylinder mounted for rotation within the housing, separate racks movably mounted within the housing and cooperating with the cylinder for stopping the gravitation of cotton means for positively and automatically actuating the racks intermittently to intermittently present cotton to the cylinder at different levels and to deliver trash to the receiving means, means for rotating the cylinder to advance its teeth into the stopped cotton presented thereto, a stripper cooperating with the cylinder, and means for doffing cotton from the cylinder and directing it to the outlet.

6. The combination with a housing having a cotton inlet in the upper portion thereof, trash receiving means communicating with

- the lower portion thereof, and a cotton outlet, of superposed racks movably mounted within the housing, a toothed cylinder mounted for rotation within the housing and 5 adjacent to and cooperating with the racks to retard cotton, means for actuating the racks positively and automatically in properly timed succession to intermittently stop the gravitation of cotton through the housing from the inlet toward the trash receiving means and to present the cotton when 10 stopped to the toothed surface of the cylinder, and means for actuating the cylinder to advance the teeth into the gravitating and stopped cotton.
7. The combination with a housing having a cotton inlet in the upper portion thereof, and a cotton outlet, of a toothed cylinder mounted for rotation within the housing, 20 superposed racks movably mounted within the housing in the path of cotton gravitating from the inlet and cooperating with the cylinder to retard the cotton, and means for automatically and positively operating the 25 racks in properly timed relation to intermittently stop the gravitation of the cotton and to present the cotton at different elevations successively to the rotating cylinder.
8. The combination with a housing having a cotton inlet and a cotton outlet, of 30 superposed toothed cylinders mounted for rotation within the housing below the inlet,

stripping means cooperating with the respective cylinders, doffing means cooperating therewith and adjacent the outlet, racks 35 cooperating with the cylinders for retarding cotton, and means for intermittently and positively actuating the racks automatically to intermittently retard the gravitation of the cotton from the inlet and to intermittently present the cotton to the toothed surfaces of the cylinders at different elevations successively.

9. The combination with a housing having a cotton inlet and a cotton outlet, of superposed toothed cylinders mounted for rotation within the housing below the inlet, stripping means cooperating with the respective cylinders, doffing means cooperating therewith and adjacent the outlet, means for intermittently retarding the gravitation of the cotton from the inlet to intermittently present the cotton to the toothed surfaces of the cylinders at different elevations successively, said means including racks 50 movably mounted in the housing, and means for automatically and intermittently actuating the racks positively to shift them into and out of the path of the gravitating cotton in 55 properly timed relation.

In testimony that I claim the foregoing as my own, I have hereto affixed my signature.

RALPH E. WILSON.
